NECKTIE

Valentine Naftali, Pelham Manor, N. Y.

Application May 4, 1939, Serial No. 271,640

1 Claim. (Cl. 2—146)

The present invention relates to neckties of the four-in-hand type, that is, the type in which a knot is formed and where the ends of the tie hang below the knot, and the general objects of the invention are to enhance the appearance of the knot and the tie and to provide a more or less novel characteristic knot.

The principal object of the invention is to obtain suitable stiffness in and along the length of that end of the tie which cooperates with the knot forming portion of the tie. By folding such cooperating end portion, usually the small end of the tie, longitudinally when the tie is manufactured or by constructing such cooperating end portion so that when folded longitudinally by the wearer of the tie, such cooperating portion will tend to remain thus folded when the knot is being formed.

Another object of the present invention is to enable a knot to be formed which may be narrower than the usual knot and which is fuller or thicker from front to back than usual, such object being maintained by so stiffening the cooperating end portion along such length thereof as may fall within the knot, and extend somewhat beyond the same, that the knot tends to maintain its fulled out or thicker condition, instead of tending to be flattened out and crushed inwardly towards the wearer of the tie.

Another object of the invention is to overcome the usual tendency of the cooperating end portion of the tie to turn or twist within and adjacent to the knot, so that when the tie is tied the depending end of the cooperating end portion of the tie will lie just back of the depending wide end of the knot forming portion of the tie, thereby increasing the neat appearance of the tie.

These being among the objects of the present invention, the same consists of certain features of construction and combinations of parts to be hereinafter described and claimed with reference to the accompanying drawings showing desirable embodiments of the invention, and wherein

Fig. 1 is a perspective view of the improved tie showing one embodiment of the invention;

Fig. 2 is an elevation slightly enlarged, parts being broken away, showing the improved cooperating end portion of the tie, and viewed towards the front thereof;

Fig. 3 is an enlarged transverse section on the line 3—3, Fig. 2;

Fig. 4 is a perspective view of the improved tie shown in the first stage of attempting to form the knot;

Fig. 5 is a similar kind of perspective view

showing that a complete turn of the knot forming portion of the tie had been made around the cooperating end portion;

Fig. 6 is a front elevation of the knotted tie according to the present invention, parts being broken away;

Fig. 7 is a side elevation of the knotted tie shown in Fig. 6;

Fig. 8 is a rear elevation of the knotted tie shown in Fig. 6;

Fig. 9 is an enlarged transverse section on the line 9—9, Fig. 8, looking in the direction of the arrows;

Fig. 10 is a face view of a portion of the lining and the cooperating end portion of the tie, showing a slight modification, and

Fig. 11 is a side view thereof.

Referring to Figs. 1, 2 and 3, the tie casing or covering includes an end portion 11, usually the small end of the tie, which cooperates with the knot forming portion 12 of the tie, usually the large end thereof, the portions 11 and 12 being connected by a neck-band portion 13, such being the usual elements of a four-in-hand tie. The tie may be made of any desirable fabric 14 such as used in neckties, to constitute the covering or casing of the tie.

Lining 15 of the tie may be made of suitable bias cut fabric and it may be stiffened longitudinally by tapes or strips 16, preferably secured to the lining by adhesive, such stiffening elements extending along the face of the lining, and to either or both sides of an intermediate line thereof, for a distance preferably extending within the cooperating end portion 11 corresponding to the length to be obtained by the ultimate knot formed in the other portion 12 of the tie, and preferably for some distance beyond the top and bottom of the ultimate knot.

Preferably each tape or strip 16 is of a width approximating the width of one-half of the lining 15. Each strip or tape 16 may be made of any suitable material, preferably fabric, such as surgeon's tape, which may be cut on the bias.

The mid-line of the lining 15 is defined by the longitudinal line of stitching 17 which connects the lining with the seam of the tie covering or casing 14. The stiffening tapes or strips 16 may be applied to the lining 15 either before or after the lining has been secured by the stitching 17 to the tie, while the tie casing or covering is wrong-side out, the same being inverted thereafter in the usual manner to position the lining within the tie.

In applying the so made tie around the neck

in order to form the knot and tie the necktie, the wearer is enabled to start the tie in the usual manner by extending the knot forming portion 12 of the tie over the cooperating end portion 11, as shown in Fig. 4, but in doing so the wearer folds the cooperating end portion 11 longitudinally preferably in the direction of the arrows in Fig. 3 so as to create a longitudinally folded portion 18 held on edge in the zone in which the knot is to be formed, as shown in Fig. 4. With a little instruction the wearer of such tie will know what to do and when the folded portion 18 is created in the cooperating end portion 11, the wearer can easily maintain such folded condition due to the stiffening provided by the tapes or strips 16, and whether one of them only is at one side of an intermediate longitudinal line of the lining or at both sides, such stiffening will tend to maintain the longitudinally folded portion 18 on edge against the shirt of the wearer to support that length of the knot forming portion 12 which extends over the on-edge standing portion 18.

In Fig. 5 there is shown the next step in forming a knot, where the knot forming portion 12 of the tie is shown at 19 as completely looped around the on-edge standing longitudinally folded length 18 of the operating end portion 11. While the partly formed knot as shown in Fig. 5 is being formed, the wearer with a little care, can maintain the longitudinally folded portion 18 of the end 11 in position to stand on edge, so that the same will fall within the ultimate knot and extend preferably above and below the knot.

Referring to Figs. 6, 7 and 8, the knot 20 is shown as completely formed and usually and preferably there will be created automatically an inward depression 21 or the like in front of the tie just below the knot. Due to the longitudinal fold 18 in the cooperating end portion of the tie, and the fact that the stiffness of the tape or tapes 16 within the knot holds the portion 18 standing on edge, as shown in Figs. 8 and 9, the knot will usually be somewhat narrower than the usual knot and the knot will have considerable fullness or thickness from front to back, as shown in Fig. 7, and is not apt to be crushed back against the wearer of the tie.

Referring to Figs. 8 and 9, it will be noted that when the knot is tied in accordance with the present invention the edges of the sides 22 of the folded over part of the cooperating end portion 11 are against the fabric covering 24 of the tie, with the fold 23 at the back of the tie, the folded over portion 18 standing on edge from front to back of the tie. In tying the knot the depression 21 in the front of the tie will be created which in turn, due to the tension on the ends of the tie, forms side pockets 24 in that section of the knot forming portion 12 which extends within and is directly underneath the knot 20. Into one of these pockets 24 the folded over length 18 of the cooperating end portion 11 will fall, depending upon whether the knot is formed by a left handed or a right handed person. The resultant effect is that when the knot is fully tied the longitudinally folded section 18 will be hidden within one of the pockets 12, and, due to the stiffness of the longitudinally folded portion 18 and the resultant condition forced in the knot of the tie, the depending lower end of the knot forming portion 12 of the tie will be somewhat humped up away from the wearer and will gradually flare away from the knot along

the edges, so that the section of the cooperating end portion 11 which depends from the knot will fall directly behind and be hidden by the depending end of portion 12 and the portion 11 will be prevented from being seen from the front of the tie.

Figs. 10 and 11 illustrate a modified construction of the cooperating end portion 11a of the tie, wherein the longitudinally folded over side lengths 25 of said portion 11a are securely held together in opposed relation as by the means of the fastening element 26, which may reside in tacking formed by stitching the said side lengths 25 together. In this way, and when the cooperating end portion 11a of the tie is made in accordance with the invention, the necessity that the wearer of the tie in tying hold manually folded the portion 11a is avoided and made unnecessary. In other respects said modified construction will serve the same purpose as in the construction previously described.

Whether a definite line of longitudinal fold is obtained in the manner of the modification referred to or is obtained manually by the wearer of the tie, it will be noted that the tie has greater flexibility along the line of the ultimate fold, thus permitting the fold line to be readily created.

On the other hand, additional stiffness for the lining can obviously be obtained by employing a lining of less soft material than usual, such as a lining like mohair, cambric-muslin, hair cloth or with rubber-like or other coatings, such characteristic of the lining extending preferably entirely across the width of the lining, so that when the cooperating end portion of a tie provided with such lining is folded longitudinally, the user may create a forced fold in the lining itself of the cooperating end portion, due to the stiffness of the lining, which will tend to hold its shape because of the fact that such relatively stiff lining has been doubled over lengthwise of itself. While such a definite fold can be created in a sufficiently stiff lining, a manufacturer of the improved tie also can fold the appropriate end of such lining longitudinally and iron a fold into it, and then the lining can be flattened out to be sewed into the necktie, while wrong-side out, but without removing the line of fold which has thus been created.

In all cases it is to be understood that when the preferred fulled out and relatively narrow knot is formed, the front cross-over portion of the knot is turned in more than usual at the sides and around the thus longitudinal folded section of the cooperating end portion of the tie which stands on edge, and when the knot is completely tied the longitudinally folded end portion will have the sides of the front of the knot extend to each side of the fold so that the cooperating end portion of the tie is not shifted to one side below the knot, and is more or less centralized on edge at points within and have some distance beyond the knot. Furthermore, the cooperating end portion of the tie along its thus stiffened length when folded longitudinally on edge in starting to make the knot, even if the fold is not positively secured as in the modification, Figs. 10 and 11, has a tendency to maintain itself while sliding the knot upwardly on the cooperating end portion, so that the knot is not likely to be crushed down.

It is to be understood that the invention herein shown and described is not otherwise limited than is defined in the appended claim.

What I claim as new is:

In a necktie of the four-in-hand type, in combination, a tubular outer fabric casing and a lin-

ing within said casing, said casing having a knot forming portion in the small end of the tie, a co-operating portion therefor in the large end of the tie, and an interconnecting neckband portion, stiffening members carried by said lining and disposed in the said knot forming portion of the small end of the tie, said stiffening members being secured on opposite sides of approximately the longitudinal axis of the lining leaving a relatively narrow space between said stiffening members, said space being unstiffened and serving as

5 a fold line to automatically fold the lining longitudinally substantially in half to provide a folded portion in the small end of the tie when the said tie is made up into a knot, the said folded portion 10 cooperating with a fold in the said large end of the tie, the said stiffening members being resistant to crushing in a transverse direction to maintain the finished knot against flattening or crushing from front to back.

VALENTINE NAFTALL.
